CLAIM

The ornamental design for a lipstick bullet, substantially as shown and described.

DESCRIPTION

FIG. 1 is a top, front and right side perspective view of our new design for a lipstick bullet;

FIG. 2 is a front elevation view of the lipstick bullet shown in FIG. 1;

FIG. 3 is a rear elevation view of the lipstick bullet shown in FIG. 1;

FIG. 4 is a right side elevation view of the lipstick bullet shown in FIG. 1;

FIG. 5 is a left side elevation view of the lipstick bullet shown in FIG. 1;

FIG. 6 is a top plan view of the lipstick bullet shown in FIG. 1; and,

FIG. 7 is a bottom plan view of the lipstick bullet shown in FIG. 1.

The broken lines showing a cup-shaped support base illustrate environmental structure that forms no part of the claimed design.
